UNITED STATES PATENT OFFICE.

JAMES F. FULLUM, OF BOSTON, MASSACHUSETTS.

AUTOMATIC AXLE-LUBRICATOR.

No. 834,289.

Specification of Letters Patent.

Patented Oct. 30, 1906.

Application filed June 8, 1904. Serial No. 211,262.

To all whom it may concern:

Be it known that I, JAMES F. FULLUM, a citizen of the United States, and a resident of Boston, Massachusetts, have invented an improvement in an Automatic Axle-Lubricator, of which the following description, in connection with the accompanying drawings, is a specification, like letters on the drawings representing like parts.

10 My invention is a self-lubricating oiler for vehicle-axles, and while particularly intended for heavy vehicles it is equally adapted for use with all kinds, even the lightest vehicles.

15 My invention relates to that class of oilers in which a removable oil carrier or tube is carried in a longitudinal groove in the end of the axle and provided with a strip of felt for conveying the oil from the tube or receptacle by capillary attraction to the surface to be lubricated. Various devices of this general character have heretofore been devised and suggested; and the object of my invention is to obviate some of the objectionable features and provide various additional improvements. One of the serious difficulties encountered, especially with heavy wagons, is the liability of automatic oilers to clog with grit, and another objection 20 relates to the means for removing the oiler, and accordingly I have invented a construction which provides a sand box or receptacle for preventing any sand or grit from getting into the oiler, and I provide a construction 25 which enables the oiler to be instantly removed simply by inserting a hook therein and pulling it out from the axle. In addition to these features I provide a construction which affords an extra large oiling-surface and maintains the felt in proper operative position, preventing it from matting down. My construction also affords great 30 strength and durability.

35 Other features of advantage and all the constructional details will be pointed out more at length in the following description, reference being had to the accompanying drawings, in which I have illustrated preferred embodiments of my invention.

40 In the drawings, Figure 1 is a view in side elevation of an axle provided with my invention, parts being broken or sectioned for convenience of illustration. Fig. 2 is a transverse sectional view thereof on the line 45 2 2, Fig. 1. Fig. 3 is a similar sectional view of the construction for heavy vehicles. Figs.

4 and 5 are sectional details of the construction shown in Fig. 2, Fig. 4 showing the felt as just inserted, and Fig. 5 showing it soaked full of oil. Figs. 6 and 7 are similar sectional views of the construction shown in Fig. 3, also illustrating the felt before and after the oil is applied. Fig. 8 is a central vertical longitudinal sectional detail of the outer end of the oil-tube. Fig. 9 is a perspective view 50 of the oil-tube. Fig. 10 is a perspective view of the felt for the oil-tube. Figs. 11 and 12 are top plan views of the opposite outer ends of an axle provided with my invention.

My invention may be applied to any usual axle, and for convenience of illustration I have shown, in Fig. 1, a usual axle a , such as is commonly found in the better class of light vehicles. This axle is grooved longitudinally on its upper side, as indicated at a' , to 55 receive an oil-tube a^2 . The groove a' has a special shape, being outwardly flared at its upper edges, as indicated at a^3 , Figs. 2 and 3, and the tubes a^2 are also flared, those used for the smaller-sized vehicles being laterally flared at both edges a^4 and a^5 , as indicated in Figs. 4 and 5, and those used for the larger vehicles being flared at one side only, as indicated in Figs. 6 and 7. Within the tube I provide a long strip a^6 of pressed felt, as 60 indicated in Fig. 10, constituting an oil containing and delivering member for applying oil to the moving surface above it, this strip having a length corresponding to the oil-receiving chamber of the tube. The purpose 65 of the flaring is to permit the oil to flow freely throughout the length of the tube and give a larger oiling-surface, while also permitting the felt to loosen up and enlarge at its upper surface, as indicated in Figs. 5 and 7, the flaring edges of the tube presenting shoulders or supporting-surfaces for holding 70 up the felt and preventing its matting down or becoming depressed within the tube. Also the outward bends or flaring edges of 75 the tube give strength to the latter, so that the tube is not likely to become bent or broken. At its outer end the tube is filled with lead or other suitable closing substance, as indicated at a^7 , and is vertically perforated 80 or provided with a convenient notch or hole a^8 for receiving a hook a^9 , (see Fig. 1,) whereby the tube may be instantly withdrawn when the retaining-cap (not shown) is unscrewed from the threads a^{10} of the axle. 85 Usually the tubes are sent to the trade with the closed end a^7 left uncut, as shown in Fig.

8, and when prepared for use they are cut away at a^{12} , as shown in full lines, Fig. 9, and indicated in dotted lines, Fig. 8. The horizontal surface of the ledge a^{12} rests just 5 below the threads a^{10} of the axle, so that the oiling-tube is not disturbed in any way by the screwing of the retaining-nut on or off from the axle. The ledge a^{12} terminates in a shoulder a^{13} in position to be retained by the 10 nut of the axle.

In the larger class of vehicles, especially the heavy wagons used in hauling heavy loads, there is great trouble in this class of device, because of the accumulations of sand 15 in the oiling-tube, and consequently the oil and felt or cotton become gritty. For obviating this trouble I leave the rear wall a^{14} of the tube straight, so that the rear flaring edge of the axle-groove (see a^{15} , Fig. 11, and a^{16} , 20 Fig. 12,) co-operates therewith in forming a sand-box for catching and retaining all the sand as the wheel moves forward and preventing said sand from reaching the felt a^6 and interior of the oil-tube.

25 Figs. 11 and 12 show the opposite outer ends of an axle on which the wheels rotate in the direction of the arrows when the vehicle is moving forward. In practice I have found that this materially increases the efficiency of 30 the device and is a great convenience as well, as it is readily cleaned and tends to maintain the wheel, axle, and tube in proper condition for a long period of time.

In use all that is necessary to do is simply 35 to remove the retaining-nut from the axle and then insert the hook a^9 and quickly slide out the oil-tube and felt. Thereupon the oil-tube is filled with oil, either by pouring the oil along the edges of the felt throughout 40 the length of the tube, or, if desired, the felt is simply lifted out from the oil-cavity of the tube, and when the latter has been properly filled the felt is reinserted in the tube and permitted to absorb the oil. The tube and 45 its contained felt are then simply shoved back into place, the nut is screwed in proper position, and all is in readiness for continued service of many weeks before further attention is needed.

50 I am aware that many changes in form and arrangement of parts may be resorted to without departing from the spirit and scope of my invention, and I wish it also understood that certain features of my invention 55 may be used with advantage with old constructions, although I prefer to employ the entire construction as shown, and accordingly in some of my claims I have set forth the entire construction, while other claims are 60 limited in only certain details.

Having described my invention, what I claim as new, and desire to secure by Letters Patent of the United States, is—

65 1. In an axle-oiler, an axle having a longitudinal groove in its upper surface, combined

with a removable oil containing and delivering member, said groove being U-shaped with deep parallel sides, whose extreme upper portions are flared divergently upward, the depth of said groove being sufficient to 70 maintain upright said removable oil containing and delivering member and said flaring portion acting to support the top of the latter and afford an extended oiling-surface.

2. An axle-oiler, comprising a removable oil-tube flaring divergently upward at its top opening, and a removable oil-delivering strip occupying said tube and adapted to spread out into supported position against the flaring sides of said tube for delivering oil to the 80 axle.

3. An axle-oiler, comprising an oil-tube containing absorbent material for delivering oil therefrom, and an axle grooved at its upper side to receive said tube, said tube having a vertical rear side and said groove having a flaring rear wall, co-operating with said vertical rear side of said tube to form a sand-receiving cavity at the rear side of said tube, for catching the sand and grit as the wheel 90 turns forward, thereby preventing the same from entering said tube.

4. An axle-oiler, comprising a tube having its forward longitudinal side outwardly flared and its rear longitudinal side plane, and an axle having a groove in its upper side outwardly flared at both longitudinal edges for sustaining said flared forward side of the tube and for providing a sand-box immediately 95 behind said plane side of the tube.

5. In an axle-oiler, a tube having a longitudinal oil-receiving cavity open throughout its length on its upper side and a shouldered closure at its outer end and upper side, the top surface of the extreme end of said closure 105 being smooth, and said end containing a vertical hook-receiving hole for instant withdrawal of said tube.

6. An oil-tube for an axle-oiler, closed excepting on its upper side, the outer end thereof being closed with readily-cut material such as lead and containing a vertical hole, whereby said end may readily be cut to fit an axle without interfering with the withdrawing means.

7. A vehicle-axle having at its opposite ends longitudinal grooves in its upper side, oil-tubes contained therein for endwise removal, each tube having a vertical rear side, whose top edge extends approximately flush with the circumference of the axle and said axle having a longitudinal cavity at the rear side of each of said tubes, formed by said groove and the vertical side of the adjacent tube for collecting sand.

8. In an axle-oiler, a removable oil-tube, and a strip of absorbent material for distributing the oil therefrom, said tube having laterally-projecting supporting means extending longitudinally at the top thereof en- 130

gaging underneath the top edges of the strip for supporting and suspending said material and for preventing its matting down into the tube.

- 5 9. An axle-oiler, comprising a groove in the upper side of the axle, a removable oil-tube therein, and a strip of absorbent material in said oil-tube, said tube having means coöperating with said strip for providing an enlarged oil area extending laterally at the

top opening throughout the length of said tube.

In testimony whereof I have signed my name to this specification in the presence of two subscribing witnesses.

JAMES F. FULLUM.
